Primary Examiner — Cathy A MacCormac

(74) Attorney, Agent, or Firm — Holland & Hart, LLP

(57) **CLAIM**

The ornamental design for an animal treat dispenser, as shown and described.

DESCRIPTION

FIG. 1 is a perspective view of the animal treat dispenser, showing my new design;

FIG. 2 is a front view of the design illustrated in FIG. 1;

FIG. 3 is a right side view of the design illustrated in FIG. 1;

FIG. 4 is a left side view of the design illustrated in FIG. 1;

FIG. 5 is a rear view of the design illustrated in FIG. 1;

FIG. 6 is a top view of the design illustrated in FIG. 1; and,

FIG. 7 is a bottom view of the design illustrated in FIG. 1.

The broken lines in the drawings are for the purpose of illustrating unclaimed portions of the animal treat dispenser and form no part of the claimed design.
